UNITED STATES PATENT OFFICE.

CHARLES D. ARMSTRONG, OF PITTSBURGH, PENNSYLVANIA, ASSIGNOR TO ARMSTRONG CORK COMPANY, OF PITTSBURGH, PENNSYLVANIA, A CORPORATION OF PENNSYLVANIA.

DESIGN FOR A RUBBER HEEL.

Application filed May 11, 1922. Serial No. 2,197. Term of patent 14 years.

To all whom it may concern:

Be it known that I, CHARLES D. ARMSTRONG, a citizen of the United States, residing at Pittsburgh, in the county of Allegheny and State of Pennsylvania, have invented a new, original, and ornamental Design for Rubber Heels, of which the following is a specification, reference being had to the accompanying drawing, forming part thereof, in which—

Figure 1 is a perspective view of a rubber

heel having nail button decorations embodying the design.

Figure 2 is a cross-section on the line II—II of Figure 1.

I claim:

The ornamental design for rubber heels, substantially as shown.

In testimony whereof, I have hereunto set my hand.

CHARLES D. ARMSTRONG.
